WIRE TIGHTENER

Henry G. Smith, Cuyahoga Falls, and Clyde B. Macdonald, Akron, Ohio

Application April 3, 1936, Serial No. 72,576

12 Claims. (Cl. 140—106)

This invention relates to improvements in devices for crimping wires and other similar elements and while intended for use generally wherever it may be advantageously employed, the invention is particularly adapted for use in a tool for tightening fencing wires.

Objects of the invention are to provide a wire tightener of simple, durable construction which can be manufactured at a low cost; which may be conveniently used to quickly tighten a wire and which will be very efficient in use.

Other objects are to provide a tightening device which will shorten a wire by crimping without forming sharp bends whereby the wire may be subjected to great longitudinal stress without straightening the crimped portion and may be crimped without cracking, breaking, elongating or otherwise affecting its strength or durability.

Other objects and advantages will be apparent from the following description when considered in connection with the accompanying drawing in which there is shown an illustrative embodiment of the invention, it being understood that the invention is not confined to the particular adaptation illustrated and that changes and modifications may be made which come within the scope of the claims hereunto appended.

In the drawing:

Figure 1 is a longitudinal view of a crimping device constructed in accordance with this invention.

Figure 2 is a similar view showing the handle portion as it is swung to an open position for receiving a wire preparatory to crimping the same, a portion of the handles being removed to conserve space.

Figure 3 is a similar view showing the handle portions swung to an open position.

Figure 4 is a cross sectional view taken as indicated by the lines 4—4 of Figure 1.

Proceeding now to a detailed description of the invention with reference to the illustrated adaptation thereof disclosed in the drawing, the numeral 4 denotes a cross head formed of a flat piece of steel or other suitable material.

The numeral 5 denotes a handle member which is preferably formed of a flat piece of steel and which is hingedly secured to the cross head 4 by means of a bolt 7. The bolt 7 extends through a suitable bore 25 located adjacent the upper corner of the handle 5 and which is secured in a bore 6 formed in the cross head 4 at a point adjacent the upper edge thereof and spaced inwardly from one end thereof. A like handle member 26 is likewise secured to the cross head 4 by

means of a bolt 8 which is positioned through the bore 21 at a point adjacent the upper outer corner thereof. A bolt 8 is secured in a bore 28 which is formed in the cross member 4 as shown in the drawing. The inwardly presented edges of the handle members 5 and 6 are straight and the cross head 4 is provided adjacent the lower edge thereof with stops which may be in the form of the pins 9 and 10 set to limit the inward movement of the handle members 5 and 6.

The numeral 11 denotes a relatively large stud which is positioned adjacent one end of the cross head 4 in close, spaced relation to the lower corner thereof, and which projects at a right angle therefrom. The handle member 5 is provided with a relatively wide head which projects laterally outward from the shank portion thereof.

The shank of the handle member 5 is provided on the outward lateral side thereof with a notch 13 which is adapted to receive one side of the stud 11, when the handle member 5 is swung to an outward position as shown in Figure 2.

As shown in the drawing the handle member 6 is of exactly the same shape as the handle member 5 but is oppositely positioned, with the projecting portion of the head presented laterally outward. The shank of the handle member 6 is provided on the outer lateral edge thereof with a notch 14 for receiving the one side of the stud 12 which projects at a right angle from the forward face of the cross head 4 to limit the outward movement of the handle 6 as shown in Figure 2.

The cross head 4 is also provided with a relatively longer stud 15 which projects at a right angle from the forward face thereof and which is positioned adjacent the upper edge thereof at a point equidistant between the inner edges of the handle members 5 and 6.

In the particular adaptation of the invention shown in the drawing, the member 5 is provided with two studs 16 and 17 which project from the forward face thereof in parallel relation to the studs 11 and 15. The studs 16 and 17 are positioned in spaced relation on the enlarged portion of the handle member 5 and are disposed in a straight line drawn between the studs 11 and 15. The stud 16 is positioned adjacent the outer lateral edge of said enlarged portion of the handle member 5 and the head portion is provided adjacent the inner lateral edge thereof with a stud 17.

The stud 17 is of approximately the same length as the stud 11 and the stud 16 is relatively longer and is of approximately the same length as the stud 15. The enlarged portion of the handle 55

member 6 is likewise provided with studs 18 and 19 which project from the forward face thereof in parallel relation to the studs 12 and 15. When the handles 20, 21 are in a closed position as shown in Figure 1 the studs 19 and 19 are disposed along a straight line extending between the studs 15 and 12. The stud 18 is positioned adjacent the inner lateral edge of the handle member 6 and corresponds in length to the studs 11 and 12. The stud 19 is positioned adjacent the outer edge of the enlarged portion of the handle member 6 and is relatively longer than the stud 18, it being preferably formed of the same length as the studs 15 and 16.

15 The handle member 5 may be provided with suitable handles 20 and the handle member 6 with the handle 21. The handles 20 and 21 may be formed of wood or any suitable material and may be secured to the handles 5 and 6 by means 20 of the screws 22.

In use, the handles 20 and 21 are swung to an outward position as shown in Figure 2. In this position the long studs 15, 16 and 19 are positioned along a straight line running parallel 25 to and adjacent the upper edge of the cross head 4, while the shorter studs 11, 17, 18 or 12 are disposed in a straight line running parallel to and adjacent the lower edge of the cross head 4. The said studs are thus positioned in parallel rows 30 spaced apart a sufficient distance to permit a straight wire or other element to be positioned between the rows of studs as shown in Figure 2. As the studs 15, 16 and 19 are relatively longer than the studs 11, 17, 18 and 12 the operator may 35 quickly and conveniently position the studs 15, 16 and 19 on one side of a wire; with the studs 11, 17, 18 and 12 positioned on the other side thereof whereupon the handles 20 and 21 are operated to the position shown in Figure 3 which 40 moves the studs 16 and 19 downwardly and moves the studs 17 and 18 upwardly, thus crimping the wire as shown in Figure 3. As the studs 15, 16, 17, 18 and 19 are cylindrical and as pressure is first 45 exerted by the studs 17 and 18 the wire is moved inwardly and crimped without elongation.

In the particular adaptation of the invention shown, the upwardly presented edges of the studs 11 and 12 are flattened to reduce the angle of bend at this point and permit the wire 23 to move 50 inwardly from both ends of the device.

In using the device herein described for tightening fence wires as many crimps may be formed in a wire as is necessary to properly tighten the same. It will thus be seen that we have provided 55 simple, efficient means which may be quickly and conveniently used to take up slack in a wire or similar element and which will form a crimp in a wire which will not injure the wire and which will remain in the wire even when it is 60 subjected to great longitudinal stress.

Having thus illustrated our invention and described the same in detail, what we claim as new and desire to secure by Letters Patent is:—

1. In a device of the character described, a 65 cross head having three studs projecting at a right angle from the forward face thereof; two handle members hingedly connected to said cross head at spaced points adjacent the upper edge thereof; two studs projecting from each handle member in parallel relation to the first named studs; said handle members adapted when swung outwardly to position said studs in two spaced rows adapted to receive wire therebetween and adapted when swung inwardly to aline said studs 70 in a single row to crimp said wire.

2. In a device of the character described, a cross head; spaced parallel studs projecting from one side thereof; handle members hingedly connected to said side of said cross head for movement in a plane disposed longitudinally thereof; similar studs projecting from each handle member, said studs arranged on said handle members so that a wire may be positioned between certain of said studs and the handles operated to crimp the wire. 5

3. In a device of the character described, a head, studs projecting from one side thereof, a handle member hingedly secured thereto for limited movement in a plane disposed longitudinally of said side, studs on said member; said studs being arranged in two parallel rows when the members are swung to one position whereby a wire may be received between the rows and arranged to crimp the wire when the member is swung to an 10 operative position. 15

4. In a device of the character described, a head; spaced studs projecting from the one side thereof, members hingedly secured to said head for limited swinging movement between said studs, a handle on each member, two projections 25 on each member, said projections spaced apart to provide a wire receiving space therebetween, said projections and studs being arranged in two parallel rows when the members are moved to an open position whereby a wire may be received 30 between the rows, and arranged to crimp said wire when the handles are swung to an operative position.

5. In a device of the character described, a head, a handle member hingedly secured thereto 35 for limited swinging movement in the plane of one side of said head; spaced lugs on said head, spaced lugs on said member; said lugs arranged, when the member is swung to one position to receive a wire between the lugs on the head and 40 between the lugs on the member and means to swing said member and move said lugs into forced contact with said wire.

6. In a device of the character described, a flat, elongated head, two members hingedly secured thereto at spaced points for turning movement on one face thereof, said members provided with handles which project beyond one edge of said head; lugs projecting from said face, one of said lugs positioned between said 50 members, the other lugs being relatively shorter with one of said lugs positioned outwardly from each of said members; a long and a short lug on each member, said lugs arranged when the handles are swung to an open position to form two 55 spaced rows adapted to receive a wire therebetween with the short lugs on both the head and the members positioned in one row and the longer lugs in the other row and arranged when said handles are operated to rotate said members to move said lugs in staggered relation against said wire substantially as and for the purpose herein set forth. 60

7. A wire-tightening device comprising a pair of plates pivotally connected for relative angular 65 movement, handles extending from said plates to form a portable, manually operable tool for tightening slack wires, a pair of studs upstanding from one plate and at least one stud upstanding from the other, said studs being so positioned 70 that with the plates in one position they may be moved toward a wire so that at least two of said studs will lie on one side thereof and the other will lie on the other side whereby, on relative movement of the plates, the studs form a kink 75

- in the wire between extended portions thereof.
8. A wire tightener comprising a pair of plates each hinged on an axis perpendicular thereto, handles extending from said plates to form a portable, manually operable tool for tightening slack wires, a pair of projections extending laterally of one plate adapted to engage a wire at points spaced therealong, at least one projection extending laterally of the other plate in the same direction as the first-mentioned projections, said one projection being adapted on movement of one plate relative to the other, to form a kink in the wire between the first-mentioned projections.
15. A wire tightener comprising a pair of plates each hinged about an axis perpendicular thereto, handles extending from said plates to form a portable, manually operable tool for tightening slack wires, wire engaging means extending substantially perpendicularly from both plates in the same direction, whereby on angular movement of one plate relative to the other, said means form a kink in a wire extending therebetween.
25. 10. A wire tightening device comprising a head, two members secured thereto for swinging movement in the same plane, handles extending from said members to form a portable, manually

operable tool for tightening slack wires, two studs on each member, said studs being adapted when the members are swung to one position to receive a wire between the studs on each member and adapted to crimp the wire when the members are swung to an operative position.

5 11. In a wire tightener, a head, a plurality of members hingedly secured thereto for swinging movement thereon, handles extending from said members to form a portable, manually operable tool for tightening slack wires, spaced studs on each member, the studs on each member being adapted to receive a wire therebetween whereby a relative forced movement of the members will 10 crimp the wire.

15 12. In a wire tightener, a head, a member hingedly secured thereto for rotary movement thereon, handles on said head and member to form a portable, manually operable tool for tightening slack wires, two studs on said member, said studs being positioned in spaced relation and in spaced relation to the center of rotation with one stud positioned a greater distance from the center of rotation than the other and at least one stud projecting from said head at a 20 25 point adjacent said member.
